UNITED STATES PATENT OFFICE

2,622,204

MASS SPECTROGRAPH

Albert E. Shaw and Wilfrid Rall, Chicago, Ill., assignors to the United States of America as represented by the United States Atomic Energy Commission

Application October 31, 1946, Serial No. 706,880

7 Claims. (Cl. 250—41.9)

1

This invention relates to a mass spectrograph, and more specifically, a mass spectrograph comprising a double focusing system for use in the analysis and examination of solid materials.

The present double focusing mass spectrograph conforms to the so-called "Mattauch Theory," wherein the structural design of the instrument incorporates velocity and directional focusing of a heterogeneous ion beam upon a recording device, such as a photographic plate.

The principal object of the present invention is to provide an improved mass spectrograph which will make possible the determination of small percentages of impurities in uranium, thorium and other heavy metals in relatively short periods of time without necessitating unusual skill on the part of the operator.

A more specific object of the invention is to provide a unitary sub-assembly for collimating and electrostatically deflecting the ion beam. This assembly is operatively coupled to a removable ion source and a magnetic deflecting unit in such a manner that the combination of the collimating slits and the electrostatic condenser will produce parallelism of the ion beam upon entering the magnetic deflecting unit of the mass spectrograph.

A further object of the invention is to provide a unitary collimating and deflecting sub-assembly which is easily removable as a complete unit which can be accurately adjusted for parallelism and alignment external to the spectrographic vacuum system.

A further object of the invention is to provide a photographic plate positioner unit for adjusting and operating the photographic plate in order to secure a plurality of successive exposures without removal of the photographic plate from the vacuum system.

A further and more specific object of the invention is to provide a removable ion source which will accommodate the rapid insertion of the sample to be analyzed, simple adjustment of a sample electrode, and the entire removal of the ion source from the mass spectrographic system.

The improved apparatus of the present invention includes various novel and useful structural features and combinations of those features which contribute to its successful operation. These various structural features and other objects and advantages of the invention will be made more apparent by reference to the accompanying drawings and the following description of a preferred embodiment thereof. In the drawings:

2

Fig. 1 represents a plan view, partly in section, showing a mass spectrograph embodying the invention;

5 Fig. 2 is an enlarged fragmentary longitudinal cross sectional view of the removable ion source;

Fig. 3 is an enlarged fragmentary longitudinal cross sectional view, partly in section, of the unitary collimating and electrostatic deflecting assembly;

10 Fig. 4 is a transverse cross sectional view of the collimating condenser slit taken along the line 4—4 of Fig. 3;

Fig. 5 is a transverse cross sectional view of the anterior portion of the magnetic deflecting unit taken along the line 5—5 of Fig. 3;

15 Fig. 6 is an enlarged fragmentary plan view, partly in section, of the photographic plate positioner unit attached to the magnetic deflecting unit, as shown generally in Fig. 1; and

20 Fig. 7 is a vertical cross-sectional view, partly in elevation, of the photographic plate positioner unit, taken along the line 7—7 of Fig. 6, of a mass spectrograph.

25 In general, the mass spectrograph of the present invention, as shown in Fig. 1, comprises an ion source 12, wherein ions are produced by a high frequency spark discharge developed between an outer electrode and a central electrode containing a specimen of the material to be analyzed. The discharge occurring between these electrodes produces ions which subsequently are accelerated to the cathode region where they are collimated. The ion source 12 is a self-contained vacuum tight unit which is readily removable from the remainder of the mass spectrographic system so that a new specimen, to be analyzed, can be easily inserted into the mass spectrograph in order to facilitate rapid determinations.

30 40 The ion source 12 is attached to a collimating and electrostatic deflecting unit, generally illustrated by numeral 14, by a vacuum tight connection. The accelerated ions developed by the ion source 12 enter the collimating and electrostatic deflecting unit 14 and are then collimated and deflected by the associated components of

35 45 said unit 14, so that the ion beam will be substantially parallel upon entering a magnetic deflecting unit, shown generally by numeral 15. The associated ion beam is then deflected magnetically so as to impinge upon a recording means positioned adjacent to the magnetic deflecting unit 15 and hereinafter described in detail.

40 45 Referring to Fig. 2 the ion source 12 comprises a central electrode 20 which may be a solid specimen of the sample to be analyzed or may

be a small tube of, for example, nickel or silver, into which the sample under examination is packed.

The sample electrode 20 is mounted and held in central position by an electrode holder 22 on a rod 23 which extends centrally through an aperture 26 positioned in an annular face plate 28. The rod 23 also extends through a central aperture 24 in an annular ring 27 and extends outwardly through a vacuum tight seal assembly, generally indicated by numeral 36 and herein-after described in detail. The central electrode 20 is mounted within an ion source housing generally indicated by numeral 13 which consists of the vacuum tight assembly 36, a flexible bellows 34, the annular ring 27, an insulating cylindrical member 38, for example, a heavy walled glass tube, and the annular face plate 28 wherein the insulating member 38 is mounted in conventional manner by a plurality of insulating rod members 39 which are attached to the plate 28 and the ring 27. The rods 39 being preferably spaced approximately 120° around the longitudinal axis of the unit 12. The rod 23 is attached to a clamp nut 25 which is adjusted by a drive screw 27A so that an inward-outward travel is produced on the rod 23. The rod 23 extends through the vacuum seal assembly 36, which comprises an annular cap plate 40 and an annular disc 41, which threads into said plate 40. The disc 41 compresses upon an inner annular ring 44 which in turn compresses an annular resilient gasket 45, which conforms to the outer periphery of the rod 23, so as to afford a vacuum tight seal. The cap plate 40 is soldered to a flexible bellows 34, which in turn, is similarly attached to said annular ring 27 thereby making flexible connection therebetween. The flexible bellows 34 and the rod 23 are adjusted by means of an adjusting screw 46 of which there are three and 120° apart which threads through said cap plate 40. Springs 47 which are three in number and 120° apart and 60° from said screws 46 are extended between said cap plate 40 and said annular ring 27 to afford tension therebetween. An annular groove 48 is machined in the posterior face of the annular ring 27 wherein an annular resilient gasket 49 is embedded; and similarly a corresponding groove 51 is machined in the anterior surface of the annular face plate 28 wherein an annular resilient gasket 53 is embedded so that the insulating tube 38 may be inserted and compressed by drawing up on the insulating members 39 by adjusting the take up screws 42. The aperture 26 is greater in diameter than the outer diameter of the rod 23 which extends through said aperture 26 so that the annular face plate 28 is electrically insulated from the central electrode 20. The outer electrode generally designated 30 comprises an annular anode cap 31 composed of material, such as stainless steel and having a central axial aperture 32. The cap 31 is held by means of friction to an outer telescopic shell 35 which slides upon an inner telescopic shell 35A which is attached centrally to said annular face plate 28. At the posterior portion of the outer telescopic shell 35 and attached thereto, is a disc insert 31A having a central opening therethrough. Attached to said disc 31A are clamps 33, which in turn, hold a metallic insert 37 formed of material having a high melting point, such as tantalum or tungsten, in close proximity with the central electrode 20. The shell 35 and the structure supported thereby constitute an outer electrode 30 which is insulated

from the central electrode 20 so that a discharge occurring between the electrodes produces ions which subsequently are accelerated to the cathode region.

- 5 As will be noted in Figs. 2 and 3, the plate 28 is connected to a ring 58 by one or more electrically insulating rods 50. Thus, by disconnecting the rods 50 from the plate 28, the entire ion source may be removed as a unit from the device. 10 A tubular insulating member 56 of any suitable material, such as glass, is recessed in the plates 28 and 58 and is afforded vacuum tight connections therewith as by annular gaskets 55 and 61 respectively. The collimating and electrostatic deflecting unit 14 comprises a collimating image slit indicated by numeral 64 and a collimating condenser slit 70, as well as an electrostatic condenser 79, and a parallel collimating slit 90 which are mounted in said sequence so as 15 to comprise a sub-assembly defined as a unitary collimating and electrostatic deflecting assembly. 20

The before-mentioned collimating image slit 64 is defined by an aperture in a plate 67 covered by a cap 63 which is preferably formed of an electrically conducting material, such as stainless steel, said cap 63 being mounted on an outer shell or tube 68. The shell 68 is slidably mounted on an inner shell 69 to accommodate adjustment of the spacing between the slit 64 25 and the electrode 30. It may be noted, that the shells 68 and 69 and the members 63 and 67 function as a cathode generally designated 60.

The inner telescopic shell 69 is an integral part of a tube 71, having a flange 72 connected to the 30 annular ring 58 so as to afford a rigid support for the unitary collimating and electrostatic deflecting assembly. The condenser slit 70 is shown slightly enlarged in Fig. 4 and is machined centrally in a metallic plate 73, for example, brass, and said plate 73 is mounted on the tube 71. Attached rigidly to the inner surface of the tube 71 by means of a plurality of screws 74 is an electrically insulating mounting 75.

The condenser generally designated by numeral 45 79 comprises spaced plates 80 and 82 formed of any suitable material such as brass, said plates being preferably in the form of segments of concentric circles to define a path 81 therebetween in the form of a segment of a circle. Thus the 50 plate 80 is disposed radially outwardly of the plate 82 from the common center of a curvature thereof. The path 81 preferably has a mean radius of 15.0 cm., a subtended angle of 31° 50', and a width of approximately 0.25 inch. The 55 plates 80 and 82 are attached to the insulating mounting 75 by a plurality of mounting screws.

The collimating slit 90 is disposed in an annular disc 91 which is positioned at the posterior end of said mounting 75 and affixed thereto. Positioned slightly beyond and posteriorly to said slit 90 is a monitoring collector 94 consisting of a looped wire of small diameter positioned in the path of the ion beam prior to entering the magnetic deflecting unit 15. Attached to the annular 60 ring 58 is a non-magnetic tubular housing 93 formed and fabricated to conform to and spaced from the condenser 79.

A pair of electrical contacts 97 are provided to provide an electrical connection and support for the condenser 79 which is provided with spring clips 98 engaging the contacts 97 and making electrically conducting connections to the condenser plates 80 and 82. Each of the contacts 97 is supported from the tube 93 by an electrically insulated vacuum seal 95 having a

vacuum-tight connection to the tube 93. A similar contact 102 engages a spring slip 101 attached to an insulated lug 100 on the disc 91 to afford an electrical connection to the collector 94.

It may be noted, that the structure comprising the image slit 64, the condenser slit 70, the condenser 79 and the parallel slit 90 constitute a unit or sub-assembly which can be simply removed from the mass spectrograph. This affords an efficient method to adjust and establish the correct interrelationship and alignment between the slits 64, 70 and 90 and the condenser 79 by optically projecting a light beam through the image slit 64 and visually correcting the internal alignment of these component members by the alignment of the exit light beam.

The condenser housing 93 is attached to the magnetic housing 17 by means of a plurality cap screws 110, preferably four in number, and a gasket 83 being provided to afford a vacuum-tight seal.

As shown in Figure 5, the housing 17 comprises upper and lower magnetic pole pieces 112 and 113 and spacers 114 of non-magnetic material interposed therebetween, the spacers 114 being preferably about 0.125 inch thick. Thus, the pole pieces 112 and 113 define a magnetic gap aperture or path 115 therebetween wherein the ions are deflected by a magnetic field.

At the posterior end of said magnetic deflecting unit 15 is a recording means in the form of a photographic plate positioner unit 120 for recording the ion beam which is deflected and impinges upon a photographic plate 121 which is mounted adjacent to said aperture 115 in an evacuated channel 130, as shown in Figs. 6 and 7. The photographic plate 121 which has a photographic emulsion thereon is cradled in a non-magnetic photographic plate holder 122. Operatively connected to said holder 122 is a non-magnetic rack 124, which engages a non-magnetic pinion 126 so that the rotation of the pinion 126 will afford an upward and downward motion to the photographic plate 121 so that a plurality of exposures on a single plate may be obtained.

The pinion 126 is connected to a rod 128 which extends through an opening 132 in a non-magnetic side wall 134 integrally formed with the associated spacer 114 and through a central aperture in a face plate 136 which is attached to the side wall 134. An annular ring disc 138 having an opening accommodating the rod 128 is threaded into the outer portion of the said face plate 136 and presses upon an annular ring 140 which, in turn, cups an annular resilient gasket 142; for example, rubber with sufficient compression so that the resilient gasket 142 will bear upon the outer periphery of the rod 128 to form a vacuum tight rotary seal. A rotatable knob 139 which is affixed to said rod 128 by means of a set screw 141 is operable to rotate the pinion 126. The rotation of the knob 139 may be calibrated for a plurality of successive predetermined positions by means of indentations 143, spaced on the inner surface of the knob 139, said indentations 143 being adapted to engage a conventional ball and spring assembly 145.

The photographic plate 121 may be removed from the evacuated system by opening a conventional gate lock 146 (Figs. 1 and 6) which bears upon an annular resilient gasket 148, for example rubber so as to afford a vacuum seal for said channel 130. A vacuum line 150 is provided for evacuating the device to any desired value.

In the operation of the mass spectograph, ions are produced by a discharge between the outer

electrode 30 and the central electrode 20 and said ions are subsequently accelerated to the cathode 60 where they are collimated upon entering the image slit 64.

5 The ion source unit is so designed that the outer electrode 30 and the central electrode 20 are electrically insulated from each other by the insulating member 38 and 39. This feature makes it unnecessary to provide the conventional tungsten seals through the walls of a vacuum envelope, and in addition, provides the mass spectrograph system with an ion source unit 12 which can be easily assembled and disassembled from the balance of the mass spectrograph in order that new samples to be analyzed may be inserted rapidly and efficiently.

20 The accelerated ion beam then is directed toward the collimating condenser slit 70 where said beam is collimated and then enters the electrostatic deflecting field which is developed across the condenser plates 80 and 82. The ion beam is electrostatically deflected and directed toward the parallel collimating slit 90 which tends to produce parallelism on the ion beam prior to entering the magnetic deflecting unit 15.

25 The ion beam is then deflected by the homogeneous magnetic field developed between said pole pieces 112 and 113, wherein said magnetic field, in this particular instance, is developed by energizing said magnetic pole pieces 112 and 113 by the use of a conventional electromagnet (not shown). If desired, the magnetic pole pieces 112 and 113 may be constructed of materials which are considered as permanent magnets, such as a cobalt, nickel, and aluminum alloy (Alnico V), thereby eliminating the associated electromagnet.

30 In operation, it has been found that the unitary collimating-electrostatic deflecting sub-assembly has provided a means for adjusting the critical inter-relationship of the electrostatic condenser 79 and the collimating slit system; and the alignment of these components, external to the vacuum system by optical methods, affords a 35 rapid method for adjusting the alignment and also affords a simple method for removal of the assembly in order to clean the surfaces from contaminants produced by past exposures.

40 It should also be noted that we have provided a mass spectrograph that is simple in design and construction, and has a substantially high resolving power for the determination of the isotope abundance ratios of solid materials having heavy atomic weights, such as uranium and thorium.

45 It will be apparent that modifications will be readily suggested to others skilled in the art as the result of the teachings of our invention, hence, it should be understood that our invention is not limited by specific construction hereinbefore described, which is an exemplary embodiment, and should be restricted only insofar as set forth in the following claims.

50 What is claimed is:

55 1. A unitary sub-assembly for a mass spectrograph comprising a supporting element, spaced entrant and exit collimating slits mounted on the supporting element, an intermediate condenser collimating slit mounted on the supporting element, and spaced condenser plates mounted on the supporting element and insulated therefrom defining a path between the plates, said path extending between said condenser and said slits, and contact springs having electrically conducting connections to the remote sides of

said condenser plates and adapted to engage associated support contacts.

2. A unitary collimating and electrostatic deflecting assembly comprising a shell with spaced aligned slits at opposite ends thereof, an insulating support member rigidly attached to said shell, an element comprising another slit said slit also being supported by said member, and a condenser comprising spaced condenser plates mounted on said member between said shell and said other slit, said plates defining an arcuate deflecting ion path between said other slit and adjacent to the first mentioned slit.

3. A device of the class described, comprising a housing having an orifice therein wherein a unitary collimating and electrostatic deflecting assembly is mounted, said assembly comprising a shell with spaced aligned slits at opposite ends thereof, an insulating support member rigidly attached to said shell, an element comprising another slit supported by said member, and a condenser comprising spaced condenser plates mounted on said member between said shell and said other slit, said plates defining an arcuate deflecting ion path between said other slit and adjacent to the first mentioned slit, and mounting means attached to said housing and engageable and disengageable with the collimating and deflecting assembly to afford support therefor, whereby the assembly may be removed from the 30 housing as a unit.

4. A device of the class described comprising a housing having an orifice therein, and unitary collimating and electrostatic deflecting assembly sealed within the orifice, said assembly comprising a shell with spaced aligned slits at opposite ends thereof, an insulating support member rigidly attached to said shell, an element comprising another slit supported by said member, and a condenser comprising spaced condenser plates mounted on said member between said shell and said other slit, said plates defining an arcuate deflecting ion path between said other slit and the adjacent of the first mentioned slit, and disengageable mounting means on the housing adjacent to the orifice for sealing the assembly within the orifice.

5. A sub-assembly for a mass spectrometer comprising, in combination, a source of ions of diverse energies, a housing having an orifice therein, and a unitary collimating and electrostatic deflecting assembly, the ion source being attached to the assembly, said assembly including a shell with spaced aligned slits at opposite ends thereof, a support member rigidly affixed to the shell, an element having another slit mounted upon the support member, and a condenser comprising spaced condenser plates mounted on the support member between the shell and the other slit, said plates defining an arcuate deflecting ion path between the other slit and the contiguous slit in the shell, and means for removably mounting said assembly within the orifice in the housing, said means including means to secure the assembly to the housing.

6. A sub-assembly for a mass spectrometer comprising the elements of claim 5 in combination with contact springs mounted on the remote sides of the condenser plates, and support contacts mounted on the housing in snug engagement with said springs.

7. A mass spectrometer comprising the elements of claim 5 in combination with means to record the ion currents attached to the housing adjacent to the unitary collimating and deflecting assembly.
